To all whom it may concern:

Be it known that I, JAMES A. In the drawing, Fig. 1 is a perspective view, from below, of the ornamental reflector of my invention showing principally the upper side of the front and the inside of the back portions of the reflector; and Fig. 2 is a perspective view also from below but from a viewpoint approximately at right angles to that of Fig. 1. This view shows principally the lower side of the front and the outside of the back portions of the reflector.

What I claim is:

The ornamental design for a reflector as shown.

In witness whereof, I have hereunto set my hand this 20 day of October, 1932.

JAMES A. O'NEIL.
